UNITED STATES PATENT OFFICE

JAMES A. SHEPARD, OF MONTOUR FALLS, NEW YORK, ASSIGNOR TO SHEPARD-NILES CRANE & HOIST CORPORATION, OF MONTOUR FALLS, NEW YORK, A CORPORATION OF NEW YORK

ELECTRICAL CONDUCTOR

Application filed February 3, 1928. Serial No. 251,474.

The present invention relates to electric conductors of the type employed to transmit current through contact devices moving relatively to the conductors and in contact with the latter, such as are employed in supplying current to the electrical mechanism of overhead traveling cranes, and the general object of the invention is to provide a conductor suitable for such purposes characterized by its novel form and the advantages in its intended use which result from its novel form. More specifically, the object of the invention is to provide a conductor for the purpose specified of such form that it may be assembled, connected to its supports and to supply conductors and bonded in an effective and desirable manner, and without necessarily requiring any field drilling or punching operations on the conductor.

In the preferred mode of carrying out the invention, I provide one or more longitudinal slots in the flat side of the body, or of a bar-like web portion of a conductor, which may be in the form of an angle bar, a T-bar, a flat bar, or other suitable rolled shape, and I make connections to the conductors by means of set screws threaded through openings on supporting or connection parts, and having their ends seated in the conductor slots. Preferably, each such connection or supporting part is formed with a kerf or groove receiving the body or bar-like web portion of the corresponding conductor or conductors, and has one or more set screws threaded through the side wall of the part, each with its inner end received in the corresponding conductor slot.

The various features of novelty which characterize my invention are pointed out with particularity in the claims annexed to and forming a part of this specification. For a better understanding of the invention, however, and the advantages possessed by it, reference should be had to the accompanying drawings and descriptive matter in which I have illustrated and described a preferred embodiment of the invention.

Of the drawings:

Fig. 1 is an elevation partly in section of a preferred form of my invention;

Fig. 2 is a section on the line 2—2 of Fig. 1; and

Fig. 3 is a section on the line 3—3 of Fig. 1.

In the drawings A represents an elongated metallic conductor of the type commonly known as a T-bar conductor having a flange A² adapted to be engaged at its underside by a traveling contact device and having an upper vertical web A' which is engaged at suitable points along its length by conductor supports. As shown in the drawings the conductor A is suspended from a supporting structure B through insulators C bolted to the structure B. Each insulator C, of which only one is shown in the drawings, is provided with a bolt D having its head embedded in the insulator, and having its lower end threaded into a metallic block E. The latter is formed at its end side with a slot E' adapted to receive the vertical web A' of the conductor A. The conductor A is ordinarily made of mild steel, galvanized to protect against oxidation and to smooth its surface as well as to improve its appearance.

In so far as above described, the conductor and its supports do not depart from the usual practice of the art. Heretofore it has been customary to secure such a conductor to the metal blocks E by means of bolts passing through the vertical conductor web A'. This mode of connection ordinarily requires that the bolt holes be drilled or punched in the field as the exact location required for such holes ordinarily cannot be predetermined. In accordance with the present invention a groove A³ is rolled in one side of the web A' of the conductor and the latter is secured in each supporting block E by a bolt or set screw F screwed into a threaded opening formed through one side wall of the slot E'. Preferably the end F' of the bolt is tapered so that while bearing against the bottom of the groove A³ it will also fit snugly against the side walls of the groove A³ which are oppositely inclined to correspond to the taper of the bolt end. With this arrangement the conductor may be rigidly and positively secured to each supporting block E quickly and easily, and without any field

drilling, punching, or other machine operation.

The special form of the conductor A described, also facilitates the connection thereto of feeder or supply conductors, and the bonding together of sections of the conductor A when, as is frequently necessary, there are two or more end to end sections. To attach a supply conductor H to the T-bar conductor A, I advantageously employ a metallic part G of yoke-like form which fits over the vertical web A' of the T-bar conductor and is formed with a threaded opening in one limb to receive a screw FA having a tapered end FA' shaped like the end F' of the bolt F to engage the side walls as well as the bottom wall of the slot A³, thus insuring a relatively large and effective contact surface area. As shown, the bolt FA passes through the metal conductor H' at the end of the conductor H, and a nut I on the bolt FA forms a means for clamping the conductor H' against the side of the yoke G.

The adjacent ends of end to end sections of the T-bar conductor may advantageously be connected together by means of a yoke shaped part GA. The latter may be similar in form to the part G, except that the part GA is preferably elongated to permit of the use of two or more bolts FB for securing the yoke GA to each of the connected sections of the T-bar conductor. The bolts FB may be similar in form to the bolts F and FA. The yoke GA with its bolts FB form a simple and effective connection between the connected sections, which is desirably strong and rigid from the mechanical standpoint, and which provides an effective electric bond between the sections.

My invention is characterized by its simplicity, effectiveness and relatively low cost of manufacture. The expensive and time consuming labor necessary in prior assembly operations is eliminated while increasing the efficiency of the connections.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention, what I claim as new and desire to secure by Letters Patent, is:

1. The combination with an electrical conductor adapted for use in supplying current in an overhead travelling crane system and comprising a bar-like web portion having flat sides and a lower edge portion arranged to form a contact surface, of a block having

a narrow vertical slot therein, and means for assembling said conductor and block with said web portion in intimate contact with the sides of said block slot comprising a horizontal groove formed in one side and extending a substantial distance longitudinally of said web portion and a screw member extending through the side of said block and into said groove and supporting said conductor in position in said block.

2. The combination with an electrical conductor adapted for use in supplying current in an overhead travelling crane system and comprising a bar-like web portion having flat sides and a lower edge portion arranged to form a contact surface, of a block having a narrow vertical slot adapted to receive said web portion in its lower end, and means for assembling said conductor and block with said web portion in intimate contact with the sides of said block slot comprising a horizontal groove formed in one side and extending a substantial distance longitudinally of said web portion and a screw member extending through the side of said block and into said groove and supporting said conductor in position in said block, said groove and screw member being formed to provide an intimate surface contact therebetween.

3. The combination with a pair of metallic electrical conductors adapted for use in supplying current in an overhead travelling crane system and each comprising a bar-like web portion having flat sides and a lower surface arranged to form a contact surface, said conductors being provided with an anti-corrosive metallic coating, of a metallic connecting block having a narrow vertical slot therein adapted to receive said web portions in its lower end, and means for assembling said conductors in end to end relation in said block with said web portions in intimate contact with the sides of said block slot comprising a groove formed in one side and extending a substantial distance longitudinally of each web portion and screw members extending through the side of said block and into said grooves and supporting said conductors in position in said block, whereby an intimate surface contact is provided between said web portions and block while maintaining the conductor coatings unbroken.

Signed at Montour Falls, in the county of Schuyler and State of New York, this 27th day of January A. D. 1928.

JAMES A. SHEPARD.
